UNITED STATES PATENT OFFICE

JARED BARTON FLEMING, OF BALTIMORE COUNTY, MARYLAND, ASSIGNOR TO THE BLACK & DECKER MANUFACTURING COMPANY, OF TOWSON, MARYLAND, A CORPORATION OF MARYLAND

VALVE TESTER

Application filed November 24, 1928. Serial No. 150,427.

The practice of grinding poppet valves, though it may be otherwise applied, is most extensively employed in the reseating or grinding of the valves of internal combustion motors. This must be done frequently and forms a large item in the maintenance of motor vehicles and an important feature of the work of the majority of motor repair shops. When the grinding job is satisfactory 10 the valve will hold air or gas pressure, but all grinding operations are subject to error which is not easily detected.

To grind the valves in the common type of motor of the present day the cylinder head 15 is removed. This is a quite laborious operation. In accordance with the previous practice the motor has been reassembled immediately after grinding, such testing as is performed being accomplished by noting the 20 compression in each cylinder as the motor is turned over on the crank, or the quality of the work may be merely judged from the operation of the motor. Not infrequently it has been necessary to remove the cylinder head 25 a second time before the work is delivered, to correct and improve the compression in one or more cylinders, which correction is accomplished by regrinding or in some instances by cleaning the contacting surfaces. Often the 30 motor is delivered with an imperfect grinding job, the failure of the motor to operate properly being attributed to other causes.

The operation of taking down and reassembling the motor constitutes a very large 35 item in the expense of valve grinding or reseating and the necessity for duplicating this operation causes a very considerable loss to the shop, or increased expense to the owner of the motor.

40 The object of the present invention is to provide means for testing the compression or fit of each valve prior to reassembling. Various testing devices have been previously constructed, but none of them have been sufficiently successful to come into general use. The present invention relates to improved details whereby the operation of testing valves in this way is rendered practical. In the 45 form of the invention illustrated this is accomplished by applying air pressure of a

known intensity to the valve and seat in the closed position of the valve and determining and comparing the periods of time during which the different valves hold the uniform pressure thus applied. When loss of pressure 55 is immediate and air pressure is held for a short time only, the surfaces require further attention. Sometimes the defect can be remedied merely by wiping and removing particles of dirt lodged on one of the contacting 60 surfaces. In other instances grinding has been insufficient as irregularities, as pitting and the like, have not been removed from one or the other surfaces and in some cases one or the other of the ground surfaces has been 65 inaccurately formed and regrinding is consequently necessary.

In the preferred form the apparatus which is the subject of the invention comprises a cup or chamber having an opening sufficiently large to encircle the valve outside the seat, and provided with soft packing or other contacting means around the opening so that the cup can be easily pressed into air tight contact with the portions of the motor casting 70 surrounding the valve seat, so that in operative position the cup encloses the valve and seat. The apparatus also includes means for setting up any desired degree of air or other fluid pressure within the chamber and means for ascertaining or reading the pressure within the chamber, the said elements being connected together to form an integral unit 75 adapted to effect an instantaneous test by a single operation.

80 A difficulty incident to the prior art devices, aside from their slow operation and the elaborate nature of the test involved in their use, is that the check valves employed are so constructed that they will not operate 85 at the pressures conveniently available and controllable for this purpose. This difficulty, among others, has been overcome by the provision of the present apparatus.

In the accompanying drawings I have 90 shown an apparatus embodying the invention in the preferred form and in a modified form.

In the drawings:

Figure 1 is a sectional elevation of the ap- 100

paratus also showing fragmentarily a portion of the engine casting including a valve seat, a valve in closed position being also shown.

5 Figure 2 is a detailed view on an enlarged scale illustrating a special type of check valve used in this connection.

10 Referring to the drawings by numerals, each of which is used to indicate the same or similar parts in the different figures, the valve testing apparatus as shown in Figures 1 and 2 comprises a cup or chamber 1 shown in the form of a cylindrical casting open at one end at 2 to take over and enclose the 15 valve seat, and having packing 3 surrounding the opening. Figure 1 also shows the lower section of the cup at 50 made detachable from the upper section of the cup 51, said sections being connected by threads 52 or 20 in any suitable manner to provide for the use of a series of interchangeable sections 50 of different sizes so that the testing apparatus may be used to test the contacts of valves of different sizes and also to test piston contacts.

25 The disclosure also includes means for generating fluid pressure in the form of a bulb pump 4 having an inlet or suction at 5 controlled by check valve 6. The pump is connected by tube 7 with the container or chamber 1 by way of fitting 8 containing a check valve 9, which prevents the escape of fluid from the container through the pump or bulb on what may be termed the suction stroke, i. e., when the bulb is permitted to expand. The non-return valve 9 consists of a disk 10 of soft material which cooperates with a flat seat 13 disposed toward the cup. The valve or disk 10 is supported when off the 40 seat by spider 18. The valve described has great advantages in the way of ease of operation, making it possible to use the pressure generating means described, i. e., the bulb, which is the most convenient for this 45 purpose as it can be operated by one hand.

50 The apparatus also includes a pressure gauge 11 suitably connected to the chamber or container 1 by means of a fitting shown in the form of a nipple 12.

55 The operation will be easily understood from the preamble and description. The container or chamber 1 is placed with its opening 2 in contact with the cylinder casting and surrounding and enclosing the valve opening or seat 14 and valve 15. The member 1 has been described as preferably provided with packing 3 surrounding the opening. This packing may to advantage be seated in a groove 19 in the mouth or lips 60 of the opening, the packing 3, which is ordinarily in the form of a ring being inserted in the groove projecting therefrom in the form of a rib surrounding the opening. The container, or more particularly the opening therein is held in contact with the cylin-

der in any suitable manner. This may to advantage be performed manually, the left hand of the operator being placed on the closed end of the container at 17 while the bulb is operated with the other hand to generate the desired pressure. When the apparatus is of the ordinary dimensions three or four contractions of the bulb, which may be accomplished by gripping the same with the hand and releasing, are sufficient to generate some ten pounds pressure in the container provided the engine valve makes reasonably perfect contact. In accordance with the practice, the test is completed by maintaining the contact of the chamber opening with the casting and noting the time elapsed before the air escapes. The test is, of course, largely comparative as to the period required for the air to escape, making it possible to secure substantial uniformity of compression in the various cylinders of the motor. A very slight defect or variation from practically perfect contact, as the presence of an extremely small particle of dirt between the surfaces is sufficient to cause the air to be released almost immediately from the chamber so that the evidence of the necessity for cleaning or further grinding the surfaces is, by the use of the apparatus, placed instantaneously and conspicuously before the 95 inspector as he tests each valve.

100 An important feature of the apparatus, as shown, is the convenient generation of pressure inside the cup and regulation of the pressure in the cup, whereby it is made possible to hold the cup in testing, or what may be termed operative position, with one hand and apply the air pressure with the other hand. In connection with the bulb operated apparatus, the form of check valve illustrated in Figure 2 is of particular importance, the valve being so constructed, i. e., having a large area on the disk 10 which is subject to the pressure of the pump by which the valve is opened, which renders the valve capable 110 of being operated by the low pressure generated in the bulb.

115 The applicant is aware of various patents showing somewhat similar apparatus. In some of these prior patents tire valves are shown. These are not suitable for the purposes of the bulb pump as the pressure generated is not sufficient to open them. Certain of the prior patents include bulbs. One of these is a vacuum bulb and another contains no check valve, the pressure applied being merely that which results from contracting the bulb and thus reducing the volume of the confined air over the valve without introducing any additional air. It is not 120 possible by such apparatus to obtain sufficient pressure to accomplish an effective test.

125 With the applicant's bulb apparatus any desired pressure may be obtained and the operation may be repeated provided the pres- 130

sure is lost, as many times as is desired without removing the cup from operative position.

I have thus described specifically and in detail a preferred embodiment of my invention in order that the nature and operation of the same may be clearly understood, however, the specific terms herein are used descriptively rather than in a limiting sense, the scope of the invention being defined in the claims.

What I claim and desire to secure by Letters Patent is:

1. Means for testing valve or piston contact in internal combustion engines, comprising a cup constructed with an opening adapted to be placed over the contact to be tested in sealed relation thereto, and to be held in place solely by one hand, said cup being formed in two sections, a pump connected to one section and operable solely by one hand, constructed to build up the pressure in said cup to the desired degree by a succession of strokes, the other section being detachable from the first named section so as to be interchangeable with sections having openings of different size.

2. Means for testing valve or piston contact in internal combustion engines, comprising a cup composed of two separable sections, one having means for connecting said cup to a source of fluid under pressure, and the other having an opening adapted to be placed over the contact to be tested, in sealed relation thereto, said last named section being selectively interchangeable with sections having openings of different size.

Signed by me at Towson, Maryland, this 20 day of November, 1926.
